GARMENT PRESSING MACHINE

William Strobridge, Syracuse, N. Y., assignor to
 United States Hoffman Machinery Corporation,
 New York, N. Y., a corporation of Delaware

Application April 1, 1940, Serial No. 327,289

4 Claims.

(CL. 38—36)

This invention relates to garment pressing machines, and particularly to a buffing mechanism for cushioning the opening and the closing movements of the press (either or both).

The invention also contemplates certain characteristics in the buffing mechanism which becomes effective in the closing movement of the press, the purpose of such arrangement being to prevent the buffer from unduly interfering with the so-called "patting" operation, which is an operation often carried out and which involves reciprocation of the press between closed and slightly open position.

Generally stated, the buffer is of the combined spring and hydraulic type, the hydraulic mechanism operating to delay the retreat of the buffer upon the closing and upon the opening impact (either or both), while permitting a more rapid resetting of the buffer when it is inactive. According to the invention, the hydraulic mechanism also imposes some delay on the restoration of the buffer, the purpose being to keep the buffer from becoming completely restored in the short time intervals between successive pats. Thus, during the patting operation the buffer is not completely out of action, but it is not allowed a sufficient range of action to interfere with effective patting.

An important feature of the invention is that the latch and the buffer are both associated with one of the toggle elements of the press, and thus are so closely related to each other that their coaction is precisely timed.

The preferred embodiment of the invention will now be described, reference being had to the accompanying drawings, in which:

Figure 1 is a side elevation, partly broken away, showing a press embodying the invention.

Fig. 2 is a plan view of the forward lever of the primary toggle, i. e., that toggle which is operated by the foot pedal.

Fig. 3 is an enlarged view of a portion of the toggle mechanism shown in Fig. 1, closed position being indicated in full lines and open position in dotted lines.

Fig. 4 is an elevation of the rear link of the primary toggle equipped with a double acting buffer constructed according to the present invention, the buffer mechanism being shown largely in section; and

Fig. 5 is a plan view of the link shown in Fig. 4.

In its general aspects, the press proper conforms to known practice in the garment pressing

art and, hence, need be described only in general terms.

The main frame of the machine is generally indicated by the reference numeral 11. This frame has a forward standard 12 which supports the buck 13 and an upstanding portion 14 upon which the press lever 15 is fulcrumed at 16. The lever 15 carries the head 17 at its forward end and is counterweighted at 18. A tension spring 19 urges the lever in a press opening direction. A handle 21 is applied to the forward end of the lever 15 and serves as means by which the operator may draw the press closed, and is the means for reciprocating the head 17 in the well known patting operation. However, to close the press and lock it for sustained pressing operation, use is made of a double toggle linkage, well known in the art.

The so-called secondary toggle, made up of two links 22 and 23 hinged together at 24, reacts between a fulcrum 25 on the base element 11 and a fulcrum 26 carried by the bell crank 27. The fulcrum 26 is adjustable relatively to the lever by means of an adjustable bell crank 27. This is pivoted at 28 to the lever and is adjusted by turning a wheel 29. The wheel 29 is pinned to a rod 31 which is threaded at 32 into a clevis 33 fulcrumed at 34 to the upper end of the lever 27. The forward end of the rod 31 is rotatably mounted at 35 in the cross-piece 36 formed integrally with the lever 15, which at that point is bifurcated.

To operate the secondary toggle 22, 23, use is made of a so-called primary toggle, which comprises a forward lever 37 which is fulcrumed at 38 in the base 11 and the rear toggle link 39, which is pinned at 41 to the forward lever 37 and pinned at 42 to the lower link 23 of the rear toggle. To swing the forward lever 37 and close the press, there is provided a foot lever 43 fulcrumed at the rear of the press and connected by a link 44 with the forward end of the forward lever 37. Thus, depression of the pedal 43 moves the press to closed position (see Fig. 1). A coil tension spring 45 reacts between the link 23 and the base 11 and tends to break the secondary toggle.

To hold the press closed, a latch 46 is pivoted at 47 to the link 39 and has a hooked end which engages behind the roller 48 mounted on the link 23. A coil spring 49 urges the latch in an engaging direction. This latch may be released by a finger-actuated lever 51 pivoted at 52 on the lever 15 and within finger reach of the handle

21. It may be also released by depressing the foot pedal 53 against the resistance of a spring 54, the lever 53 being fulcrumed in the base 11 at 55. These two actuators are linked to a latch releasing trigger 56 which is carried on a journal 57 supported by the frame 11. One end of the trigger 56 overlies a tail on the latch 46 and when the trigger 56 is turned clockwise, the latch is forced in a disengaging direction against the resistance of the spring 49.

From the finger-piece 51, a link 58 leads to a bell crank 59 pivoted at 61 on member 14. From the other arm of the bell crank 59 a reach rod 62 leads to the trigger 56. The rear end of the foot lever 53 is connected by a reach rod 63 to the trigger 56. The parts are so arranged that depression of the finger-piece 51 or the latch pedal 53 will release the latch 46 and maintain it released.

During the patting operation, the operator holds the finger piece 51 depressed, and is thus free to open and close the press by swinging the press head up and down.

To cushion the opening and closing movements of the press, a buffer structure is carried by the rear link 39 of the primary toggle, and the details of its construction are best shown in Figs. 4 and 5. An upward extension or housing 64 is formed integrally with the link 39 and encloses a reservoir chamber 65, a closing buffer chamber 66, and an opening buffer chamber 67. A branch or extension 68 of the reservoir chamber leads between the two buffer chambers, as clearly shown in Fig. 4. The two buffer chambers are open at their outer ends and screwed into these openings are two cylinder bushings 69 and 71. In these bushings work two piston buffers 72 and 73 which are substantially identical. Their outward motion is limited by snap rings 74, one for each buffer piston, and leakage is precluded by the cup packings 75 and 76, one for each piston. Each buffer is urged outward by corresponding coil compression springs 77 and 78. From the closing buffer chamber 66 a port leads to the reservoir chamber 65 and is partially throttled by the conical end of a valve stem 79. This is threaded into the body 64 and is surrounded by a coil compression spring 81 which acts as a frictional lock to prevent loss of adjustment. Similarly, a port leads from the opening buffer chamber 67 past the conical end of a valve stem 82 which also has a retaining spring 83.

The branch port 68 from the reservoir chamber 65 is in one-way communication with both the chambers 66 and 67. This communication is afforded by one-way ball check valve assemblies, generally indicated by the numerals 84 and 85. Just before the press reaches the closed position of Fig. 1, the end of the buffer plunger 72 strikes a boss 86 on the upper end of the secondary toggle link 23. Thus, the resistance offered by the spring 77 and the resistance offered by the throttling action of the valve 79 (which resistance is adjustable) cushions the closing movement of the linkage and, hence, the closing movement of the press.

When the press starts to open, the flow from the reservoir 65 to the space 66 is more rapid, because the ball check valve 84 has comparatively larger flow capacity than that past valve 79, and the spring loading of the ball check valve is relatively slight. Thus, the plunger 72 is restored by the spring 77 at a rate more rapid than that which characterized the inward motion of the buffer plunger 72. Nevertheless, the restoration 75

of the plunger is somewhat delayed, with the result that during periodic patting and at a time when the buffing action is not important, the plunger 72 does not reach its normal outward position before the next pat occurs. Consequently, this hydraulic delay of restoration is of particular utility in conjunction with patting and has a direct relation to the use of the finger release 51 as a means for facilitating the patting operation.

When the press opens wide and reaches the dotted line position illustrated in Fig. 3, the plunger 73 engages an abutment 87 on the forward lever 37 of the primary toggle. The inward motion of the plunger 73 has characteristics substantially identical with the inward motion of the plunger 72, but, of course, the valve 82 may be adjusted to give a slower or a more rapid retreat of the plunger 73. Thus, in effect, two distinct buffers, each individually adjustable as to its buffing characteristics, are afforded. Their close association in a single structure simplifies manufacture. However, either might be used without the other. The delay of restoration of the buffer 73 is of no particular significance because the patting movement occurs when the press head is close to the buck and is not required at the position of maximum retreat or opening movement of the head from the buck. Thus, 30 while the hydraulic timing of the buffer is important in both cases, it has a particularly important function in delaying the restoration of the closing buffer, because of the effect on the patting operation.

35 While I consider it highly desirable to locate the buffer and the latch close to each other, because in this way the most precise timing can be secured, other locations for the buffer and for the latch are permissible and it must be remembered that except for lost motion and flexure of the parts, the timing of the different parts of the toggle linkage is positive. Hence, the close relationship of the two, while important, is not an indispensable feature.

40 The invention has been described as applied to a particular press, simply because this is a commercial type well known in the art and is the one with which the invention is most likely to be used. However, modifications are possible within the 45 scope of the invention and no unnecessary limitation to the specific details illustrated is implied.

50 What is claimed is:

1. The combination of a support; a buck mounted thereon; a lever fulcrumed on said support; a head carried by the lever toward and from the buck; a toggle mechanism having a portion reacting between said support and said lever and serving when the toggle approaches straightened position to move said head into operative relation to said buck and on further movement develop pressure between the head and the buck; a latch for maintaining said toggle mechanism in said pressure developing position; operator operated means for holding said latching disengaged; 55 a buffer carried by said toggle mechanism and reacting between components thereof to buff the final movement of the toggle mechanism to pressure developing position; and displaceable means forming a part of said buffing mechanism for delaying restoration of the buffing element after its displacement, whereby the head may be patted against the buck with less than the normal resistance offered by said buffing element after the first impact.

60 2. The combination defined in claim 1, in which

said buffing means comprises an hydraulic check with adjustable means for delaying the buffing response, and flow controlling means for delaying in a less degree the restoration of the buffing element.

3. The combination of a support; a buck mounted thereon; a lever fulcrumed on said support; a head carried by the lever toward and from the buck; a toggle mechanism comprising a pair of toggle links arranged to react between said support and said lever and serving as the toggle approaches straightened position to move said head toward said buck and on further movement develop pressure between the head and buck; a second toggle comprising an operator operated lever pivoted on said support, and a link connect-

ing said lever with an element of the first toggle; and buffing means carried by the last named link and comprising two independently adjustable buffers one of which reacts against a portion of 5 said first toggle as the latter approaches straightened position and the other of which reacts against said operator operated lever as the press approaches fully opened position.

4. The combination defined in claim 3, in which 10 said buffers include each an hydraulic check, an adjustable valve for varying the buffing retreat of said buffer, and check valve means affording a more rapid return flow to permit restoration of the buffer.
